Wis., a corporation of Wisconsin

Application June 29, 1949, Serial No. 101,957

4 Claims. (Cl. 241—35)

1

The present invention relates to grinding or pulverizing mills, and more particularly to those of the attrition type adapted for producing whole grain flour and other pulverized material.

An object of the invention is to provide an improved grinding or attrition mill which is of simple, durable and inexpensive construction, which is safe and economical in operation, which requires no skill or training to operate, and which is well adapted for household use to grind whole grain flour in small quantities as needed.

Another object is to provide a grinding mill having improved automatic feeding means to avoid overloading or clogging of the mill and to permit grinding of material to a substantially uniform particle size.

A further object is to provide a grinding mill having a stationary abrasive member or stone against which the grain or other granular material to be ground is spun or whirled at high-speed by centrifugal action to effect rapid attrition of the material with a light touch.

The invention further consists in the several features hereinafter described and claimed.

In the accompanying drawings,

Fig. 1 is a side elevation of the portable flour mill constructed in accordance with the invention;

Fig. 2 is a fragmentary vertical sectional view of the mill;

Fig. 3 is a fragmentary side view of the mill, parts of a fan casing being shown in section;

Fig. 4 is an elevation of the feeding end of the mill, parts being broken away and parts being shown in section;

Fig. 5 is a fragmentary bottom view of the mill, parts being broken away and parts being shown in section;

Fig. 6 is an enlarged detail sectional view of the peripheral portion of the grinding chamber of the mill;

Fig. 7 is an enlarged detail sectional view taken on the line 7—7 of Fig. 4;

Fig. 8 is a fragmentary edge view of the rotor of the mill;

Fig. 9 is a detail view of a rotor hub, parts being shown in section, and

Fig. 10 is a detail end view of the motor fan casing.

In the drawings, the numeral 15 designates a base member of the tripod type having rubber feet 16 and a central socket 17. A vertical tubular standard member 18 is detachably secured in the socket 17, as by a screw 19.

The standard member supports thereon a cup-shaped frame-forming motor fan casing 20 hav-

2

ing a horizontal axis and provided at its bottom with a tubular boss or socket 21 in which the upper end of the standard member is detachably secured, as by a screw 22. A handle 23 is secured to the top wall of the fan casing, as by screws 24. The motor fan casing has an inlet end provided with a disk-shaped screen 25 held in place as by a snap ring 26, Fig. 3, and the other end of the casing is formed with interior radial ribs 27 and 27' projecting from the casing in an axial direction. The rib 27', which is wider than the other ribs, is at the bottom of the casing and is provided with a radial set-screw 28.

An electric motor 29 extends coaxially into the fan casing and includes a stator or field member 30 and a rotor or armature 31 with a suitably journalled horizontal shaft 32, one end of the shaft carrying a bowl-shaped fan 33 near the inlet end of the casing. The motor further includes a housing comprising rigidly connected housing members 34 and 35 with cylindrical portions fitting snugly against the inner edges of the ribs 27 and 27'. The mill housing member 35 has its cylindrical portion 36 secured in place by the set-screw 28, and this housing member has a vertical wall 37 against which the ends of the ribs 27 abut. The ribbed fan casing and motor housing form cooling air passages 38 which have outlets at the projecting ends of the ribs. The shaft 32 is journalled in the motor housing, the bearing means including a ball bearing 39 carried in a hollow boss 40 formed on the housing wall 37.

The housing member 35 has an enlarged outer end portion with a marginal flange 41 which is secured, as by screws 42, to one side of a ring member 43 the housing member and ring member forming parts of a stator casing of the mill. The ring member 43 is shrunk onto an annular abrasive stone 44 having a cylindrical inner periphery. The stator casing further includes a cover member 45 which is secured, as by screws 46, to the other side of the ring member 43 and clamps therebetween a flat metal disk or wear plate 47, such as of stainless steel. The cover member has formed on its outer side a hollow elbow portion 48 with a top opening 49 in which a grain hopper 50 is detachably fitted, the hopper including a transparent wall member 51 and a lid 52. The cover member 45 has a central circular feed opening 53 which registers with a similar opening 54 in the disk 47. The elbow portion is provided in its side walls with small vent openings 49' which permit inflow of air. A metal ring plate 55, such as of stainless steel, is clamped between the stone 44 and the flange 41 of the housing member 35 and is fitted in a shallow

55 housing member 35 and is fitted in a shallow

recess 56 formed in this flange. The flat annular plate 55 has a central circular opening 57 which is slightly smaller in diameter than the inner diameter of the stone. As seen in Fig. 6, the opening 57 is beveled and flares toward the housing member 35. The bottom edge portion of the plate 55 is clamped to the ring member 43 by sheet metal clips 58 secured in place by screws 59. The abutting lower portions of the housing member 35 and ring member 43 project downwardly to form a discharge spout or nozzle 60 of oval or elongated shape, Figs. 4 and 5, and are secured together by screws 61. A bead or flange 62 is formed around the lower edge of the discharge spout for detachably holding the upper edge of a bag 63, the bag having an elastic retaining band 64.

A flat rotor disk 65 is carried by the motor shaft 32 and rotates within the stationary ring plate 55, there being a narrow slit-like annular orifice 66 between the outer edge of the disk and the inner edge of the ring plate. The space within the annular abrasive stone 44 and between the rotor disk 65 and the plate 47 forms a grinding chamber 67, and the space between the rotor disk and the vertical wall 37 of the housing member 35 forms a discharge chamber 68 communicating with the discharge spout 60. A shouldered spacer collar 69 bears against a shoulder 70 on the motor shaft, and the rotor disk 65 is clamped between the collar and a tubular hub member 71 by means of a nut-forming extension member 72 screwed onto the end of the shaft. The hub member has parallel jaws 73 engaging flats 74 on the shaft, and further has a hexagonal flange 75 bearing against the rotor disk. A felt sealing washer 76 is interposed between the collar 69 and the boss 40 of the motor housing member 35.

The rotor disk 65 carries thereon at the 40 grinding chamber side a diametrically extending sheet metal channel member 77 of U-shaped cross-section with out-turned edge flanges 78 rigidly secured to the disk, as by rivets 79. The rotor disk carries thereon at the discharge chamber side a pair of sheet-metal angle plates 80 forming fan vanes to prevent packing of flour in the discharge chamber, the angle plates being secured in place by some of the rivets 79. The base or web of the channel member 77 is parallel to the rotor disk, and the intermediate portion of the base or web is cut away to form an elongated aperture or opening 81 through which the motor shaft passes. The hexagonal flange 75 of the rotor hub 71 fits between the parallel side flanges of the channel member, these side walls being spaced at opposite sides of the rotor axis.

A sleeve 82 is slideable on the shaft extension member 72 and is pressed outwardly by a coiled spring 83 surrounding the shaft and interposed between the sleeve and the flange 75 of the hub member 71, the outer end travel of the slideable sleeve being limited by a conical shoulder 84 formed on the socket head 85 of the shaft extension member. A feed disk 86 and a bowed leaf spring 87 are clamped on the sleeve 82 by a washer 88 which is engaged by a reduced outwardly spun portion 89 of the sleeve. The feed disk has a conical peripheral portion adapted to cooperate with a beveled annular surface 90 surrounding the central opening 54 of the wear plate 47 to form an annular feed passage for the grain. The feed disk may closely approach the beveled surface 90 but does not touch it.

The leaf spring 87 projects in opposite directions from the shaft and carries at its outer ends respective pairs of U-shaped governor weights 91 of skeleton form which are disposed within 5 the channel member. The governor weights are made of sheet metal and are placed against opposite faces of the spring, the yoke portions of each pair of weights being secured to the spring by rivets 92. The edges 93 of the legs of each 10 assembled pair of governor weights are arcuate and are shaped to a diameter approximately equal to the track-forming spaces between the rotor disk and the base or web of the channel member so as to have a slidable fit in these 15 spaces. The channel member forms a guide for the governor weights and also forms a fan or impeller. It is sometimes desirable to coat or plate the rotor surfaces, particularly the tip portions of the leading faces of the channel member, with a layer of resistant metal, such as 20 chromium, so as to minimize wear. As seen in Fig. 6, the inner face of the rotor disk 65 is preferably offset inwardly from the plane of the inner face of the flat ring member 55.

25 The electric motor 29 is preferably of a high-speed series or universal type, the speed of which decreases with load. In some instances, however, other types of motors may be used. The motor is connected to a flexible conductor cord 30 94 having a terminal plug 95, the cord passing through an opening 96 in the motor housing member 35.

When the motor is at rest, the spring-pressed 35 governor sleeve 82 carrying the rotatable feed disk 86 abuts against the conical shoulder 84 on the head of the shaft extension member 72, and the feed disk is close to the beveled edge 90 surrounding the central opening 54 of the wear plate 47. Grain placed in the hopper 50 will thus be 40 prevented from entering the grinding chamber.

In operation, the motor is energized and drives the rotor 65 at a high peripheral speed. By way of example, a rotor speed of 7000 to 8000 R. P. M. has been found suitable in a mill having a grinding stone with an inside diameter of 5 five inches. After a predetermined speed is attained, the governor weights 91 are caused to move outwardly in their guide tracks by centrifugal force, the arcuate edges 93 of the weights sliding along the web of the channel member 77. In their outward travel, the spring-mounted 55 governor weights retract the feed disk 86 a sufficient distance from the edge of the feed opening 54 to permit a limited quantity of grain to enter the grinding chamber. The grain in this chamber is caused to swirl, tumble, and bounce on and around the cylindrical inner surface of the stationary abrasive stone by the centrifugal fanning action of the rotor disk and its channel member 77, thus abrading the grain and reducing 60 it to flour. The fanning action also draws air into the grinding chamber through the feed opening and forces air and flour out through the narrow annular discharge slit 66 and into the discharge chamber 68, the slit forming a 65 sieve opening for the flour. The flour falls in the bag 63, the discharge of the flour being assisted by the fanning vanes 80. The bag is sufficiently porous to permit escape of air. As more grain enters the grinding chamber, the load on 70 the motor increases and causes the motor to slow down, thus reducing the centrifugal force on the governor weights and decreasing the gap between the feed disk and the edge of the feed opening 54 to shut off the flow of grain to the 75 grinding chamber. The conical shape of the

stop shoulder 84 prevents grain kernels from being pinched between the slideable sleeve 82 and this shoulder, which would prevent the closing movement of the feed disk. As more flour is produced and discharged from the grinding chamber, the load on the motor is gradually reduced, causing the motor speed to increase slightly and opening the feed passage to admit a small amount of grain to the grinding chamber. In this manner, the quantity of grain in the grinding chamber is limited and remains substantially constant, and overloading and clogging of the mill are avoided. The grain is ground to substantially uniform particle size or mesh, eliminating the need for subsequent sifting or bolting. As the flour is discharged promptly from the grinding chamber, very little flour is present in this chamber, thus avoiding interference with the grinding operation and permitting rapid reduction of the grain to flour.

While the mill is particularly adapted for grinding grain it may also be used for grinding other granular material. In the case of a flour mill, the width of the discharge slit 66 is a few thousandths of an inch. The relative axial position of the rotor disk 65 with respect to the ring plate 55 is not critical, and may vary to some extent without substantially changing the width of the discharge slit.

What I claim as new and desire to secure by Letters Patent is:

1. In a grinding mill, a stator having a rigid inner abrasive surface of generally cylindrical shape and further having axially spaced walls, a rotor having a disk between said walls and forming with said stator a grinding chamber at one side and a discharge chamber at the other side, said rotor disk having a peripheral edge forming with an interior surface of said stator a slit-like annular discharge orifice for passage of pulverized material from the grinding chamber to the discharge chamber, said grinding chamber having an inlet for granular material to be ground, and said discharge chamber having an outlet for pulverized material, fanning means carried by said rotor disk at the grinding chamber side thereof for impelling the granular material around said abrasive surface to pulverize the material, and fanning means carried by said rotor disk at the discharge chamber side thereof, said discharge orifice being relatively narrow.

2. In a grinding mill, a stator having an annular circumferential portion of generally cylindrical shape with an inner abrasive surface and further having an end wall with a central feed opening for granular material to be ground, a rotor in said stator having a disk axially spaced from said end wall and forming with said stator a grinding chamber, said stator having therein a circular opening within which the periphery of said disk loosely fits to form an annular discharge orifice for passage of pulverized material, fanning means in said grinding chamber carried by said rotor for impelling the granular material around said abrasive surface, a centrifugally controlled closure member for said feed opening carried by said rotor and axially movable to vary the feed of granular material into the grinding chamber, and spring means carried by said rotor for urging said closure member toward closed position.

3. In a grinding mill, a stator having an annular circumferential portion of generally cylindrical shape with an inner abrasive surface

and further having an end wall with a feed opening for granular material to be ground, a rotor having a disk in said stator axially spaced from said end wall and forming with said stator a grinding chamber, the periphery of said disk forming with said stator an annular discharge orifice for passage of pulverized material, radially extending guide means carried on said rotor disk in said grinding chamber and forming fanning means for impelling the granular material around said abrasive surface, a closure member axially movable on said rotor and cooperating with said feed opening to vary the feed of granular material into the grinding chamber, and centrifugal actuating means for said closure member including centrifugally influenced members movably confined by said guide means.

4. In a grinding mill, a stator having an annular circumferential portion of generally cylindrical shape with an inner abrasive surface and further having an end wall with a feed opening for granular material to be ground, a rotor having a disk in said stator axially spaced from said stator end wall and forming with said stator a grinding chamber, the periphery of said disk forming with said stator an annular discharge orifice for passage of pulverized material, a channel member of U-shaped cross-section diametrically carried on said rotor disk in said grinding chamber and forming fanning means for impelling the granular material around said abrasive surface, said channel member having spaced side walls disposed at opposite sides of the rotor axis and further having a base connecting said side walls and spaced axially from said disk, said channel member base having an opening intersected by the axis of said rotor, a closure member axially movable on said rotor and cooperating with said feed opening to vary the feed of granular material into the grinding chamber, and centrifugal actuating means for said closure member passing through said opening in the base of said channel member and including centrifugally influenced members movably confined by the outer portions of said channel member.
